UNITED STATES PATENT OFFICE.

JOHN W. SOHN, OF ROXBOROUGH, PENNSYLVANIA, ASSIGNOR TO A. T. BAKER & COMPANY, INC., OF PHILADELPHIA, PENNSYLVANIA, A CORPORATION OF PENNSYLVANIA.

METHOD AND APPARATUS FOR BEAMING WARP.

Application filed July 27, 1921. Serial No. 437,883.

To all whom it may concern:

Be it known that I, JOHN W. SOHN, a citizen of the United States, residing at Roxborough, county of Philadelphia, and State 5 of Pennsylvania, have invented a new and useful Improvement in Methods and Apparatus for Beaming Warp, of which the following is a full, clear, and exact description, reference being had to the accompanying 10 drawings, which form a part of this specification.

This invention relates to an improvement in the method of beaming warp and apparatus for carrying out the method. The object of my invention is to provide an efficient method of beaming, whereby a warp having a relatively large number of ends may be quickly and properly beamed from tubes of yarn, by relatively cheap labor, as 20 well as to provide automatic apparatus for carrying out the method, so that the human element is substantially eliminated so far as broken or slack ends or warp threads is concerned.

25 My improved method has proven very satisfactory for beaming warp for weaving double pile fabric or plush.

Prior to my invention it has been customary for the beamer to beam chain or bale 30 warp, and during the beaming, separate and examine the warp threads or ends and splice the broken threads. As chain warp is made up of the specified number of ends or threads in strand form, laid up and coiled 35 and shipped in bale form, the threads or ends are broken in various places by handling, so that the beamer must exercise great care when beaming and splicing the broken ends, and particularly when beaming beams for plush looms. As such great care is required for beaming of this character, highly skilled beamers who command a 40 high wage must be employed.

Another object of my invention is to provide a method of beaming whereby the stock of warp may be standardized, so that the mill owner can readily make up warp beams with the required number of ends or threads without the necessity of carrying a 45

large and assorted stock of chain warp with 50 different numbers of ends.

In carrying out my invention for beaming warp having a multiplicity of warp ends, I use a creel which will hold the required number of tubes of yarn, and wind 55 the ends directly on the beam from the creel. The ends in their passage from this creel to the beam pass over various tension rollers, about a measuring drum and through an automatic stop device, supplemental to the 60 usual stop device, on the creel. This supplemental stop device is arranged to automatically stop the machine if any of the ends are slack or broken between the guiding eyes for the ends passing from the creel 65 and the measuring drum; and which will also act to stop the machine if any of the ends should break between the creel and the supplemental stop which has been picked up and carried along by other threads before 70 the regular stop on the creel fell into its stopping position, so that the danger of broken ends on the beam and two ends passing through in place of one is substantially 75 eliminated.

Fig. 1 of the drawings is a side elevation in diagram of one form of apparatus for carrying out my invention.

Fig. 2 is a perspective view, somewhat diagrammatic of a portion of Fig. 1.

In the drawing the reference character 5 designates the creel for supporting the required numbers of tubes 6 of yarn to make up a beam having the required number of ends.

The threads from each spool or tube passes through a stop which is arranged to stop the entire machine if the thread on the tube is broken. The stops are connected electrically in the usual manner with a suitable annunciator to indicate to the operator the location of the broken end, so the broken end can readily be traced and spliced. Each thread passes from its guides and stop on the creel through a guide eye on a board 7. 90 95

The various ends pass from the guide eye board 7 under and over guide rollers 8 and 9, and then through a separating device 10,

consisting of a plurality of wire eyes similar to heddles, in which alternate threads pass through the eyes while the others pass between the wires forming the eyes. One-half of the ends then pass over a separating bar 11, while the other half passes under said bar. The ends then pass from the bar 11 through a reed 12 and a supplemental stop device 13, which are arranged to keep the various ends separated so that the stop 13, which controls electrical devices, will stop the beamer if any of the ends are slack or broken, as hereinafter described.

14 is a guide roller over which the ends pass from the stop device 13, and 14' is a measuring drum about which the ends pass from the guide roller 14 to a guide roller 15. 16 is a second separating bar below the guide roller 15, one-half of the ends passing around one side thereof while the other half passes about the other side. 17 is a second reed between the bar 16 and the warp beam 18 on which the ends are wound. B is a bearing, there being one on each side of the machine for supporting the warp beam 18. 19 is a tension device or press for the warp beam comprising a longitudinal bar, which engages the ends or warp threads as they are wound on the beam, and which bar is carried by two weighted levers which are arranged to hold the bar against the wound warp with an equal pressure throughout the winding of the beam, by means of suspended weights.

25 The machine is driven by suitable mechanism hereinafter described to cause the ends to be drawn from the various tubes 6, around and through the various guides and separating devices, as well as the electrically controlled stops, by the rotation of the warp beam 18. The various guides are arranged to place the ends under tension and also to maintain the various ends separate from each other as well as to guide the various ends to their proper positions on the warp beam.

30 If any of the ends should become slack or broken between the measuring drum and the stop 13, the machine will be immediately stopped, and after the operator has spliced the end and placed it under the proper tension between the measuring drum and a point back of the stop device, the machine can again be set into motion.

35 It frequently occurs that an end breaks between the guides on the creel and some of the guides between the creel and the measuring drum, and very frequently the end will be picked up by one of the other ends and drawn ahead, thereby before the stop on the creel has time to fall into stopping position, and as the broken end continues to be drawn from the tube, the stop on the creel will fail to act.

By placing a supplemental stop device adjacent to the measuring drum or near the point of greatest tension of the ends, I am enabled to stop the machine if any of the ends break close to the beam, and thereby avoid broken ends on the beam, as well as stop the machine if an end should be broken and picked up by another end and carried forward before the creel stop acted.

In the construction shown, the beam is driven by means of a pulley 20 connected to the beam in any desired manner, which is in turn driven from a pulley 21 by a belt 22. 23 is a driving pulley on the shaft of the pulley 21 driven by a belt 24 from any suitable source. The pulley 23 is arranged to be connected to the pulley 21 by means of a clutch 25 which is arranged to be thrown by hand to connect the pulleys to each other and is retained in driving relation by an electrically actuated latch 26. This latch is arranged to release the clutch to stop the machine when the latch magnet 27 is energized.

28 is a battery or source of electrical energy one pole of which is connected to a contact 29 on the stop 13. 30 are contacts one on each side of contact 29 which are interconnected and are connected to one pole of magnet 27. The other pole of the magnet is connected to the other pole of the battery. The stop 13 is provided with a plurality of circuit closing fingers 31 of the usual type, there being one for each warp thread or end, and are arranged to separate the threads, while the tension on the ends will hold the fingers out of engagement with contacts 29 and 30. If one of the threads should become slack or broken, its circuit closing finger will drop and close the circuit through the magnet 27, release the clutch 25 and stop the machine. The stops on the creel each comprises a pivoted finger 32 having an eye through which the thread passes from the tube or bobbin 6 to its eye in the board 7. The finger 32 is connected to one pole of the battery 28 and 33 is a contact connected to one pole of magnet 27, the arrangement being such that when any of the threads break near the tube, its finger will drop, close the circuit through magnet 27, and stop the machine.

The advantages of my invention result from the provision of a method of beaming warp in which the various strands for the warp are wound direct from individual holders or tubes on a creel to a warp beam.

This beaming direct from the tubes permits the making up of warp having the proper number of ends, as required so that the mill's entire stock of yarn merely consists of individual tubes of yarn or ends instead of a large stock of baled warp of different numbers of ends.

This method of beaming also reduces the number of broken ends caused by handling the bales of chain warp, as well as those caused by the tangling of the warp while in the bale.

This method not only permits the employment of relatively cheaper labor as compared to warp beamers, but by my method the time consumed in beaming is materially reduced, which not only reduces cost of production, but also reduces the floor space required for beaming.

Having now fully described my invention, what I claim and desire to protect by Letters Patent is:

1. The method of beaming warp having a multiplicity of ends, which comprises unwinding a plurality of separated threads and imparting to them a progressive travel toward a beam and maintaining the threads under substantially the same tension by first drawing them into a single group in a prearranged order, separating said group into a plurality of groups with the threads in a prearranged order in each group, separating the individual threads from each other, then again drawing them into a single group in a prearranged order, winding the grouped threads on the beam in such order, and simultaneously and continuously subjecting to friction and pressure the warp on the beam and the threads as they pass to the beam to increase the tension of the warp as it is wound on the beam.
2. A warp beaming device having means for rotatably supporting a beam on which the threads are wound, driving mechanism for rotating the beam, electrically controlled driving means between the beam and driving mechanism, a support for a plurality of individual thread holders, a plurality of guide rolls between the beam and the support, electrical control devices between the guide rolls arranged to close the circuit through the electrically controlled driving means to stop the machine if the tension on one of the threads becomes slack, a spreader between one of the guide rolls and the electrical control devices for separating the threads into two groups and means between the last guide roll and the beam for separating and guiding the threads in a prearranged order to the beam.
3. A warp beaming device having means for rotatably supporting a beam on which the threads are wound, driving mechanism for rotating the beam, electrically controlled driving means between the beam and driving mechanism, a support for a plurality of individual thread holders, a plurality of guide rolls between the beam and the support, a guiding device between the first roll and the support for grouping the threads while maintaining the individual threads

separated from each other, electrical control devices between the guide rolls arranged to close the circuit through the electrically controlled driving means to stop the machine if the tension on one of the threads becomes slack, a spreader between a guide roll beyond the guiding device and the electrical control devices for separating the threads into two groups, and means between the last guide roll and the beam for separating and guiding the threads in a prearranged order to the beam.

4. A warp beaming machine having a beam support, mechanism for rotating the beam, electrically controlled clutch means between the rotating mechanism and the beam, four spaced guide rolls, means for directing a group of warp threads to the first roll in a prearranged order, which threads then pass about the other rolls to the beam on which they are wound, a stop device between the second and third rolls arranged to close the circuit through the clutch means to stop the machine if any of the threads are below a predetermined tension, a spreader between the stop and the second roll to divide the group of threads into two groups, a separator between the stop and spreader to separate the threads from each other before passing through the stop, a measuring drum between the third and fourth rolls, and separating means between the last roll and the beam for guiding the threads to predetermined positions on the beam.

5. A warp beaming machine having a beam support, mechanism for rotating the beam, electrically controlled clutch means between the rotating mechanism and the beam, four spaced guide rolls, means for directing a group of warp threads to the first roll in a prearranged order, which threads then pass about the other rolls to the beam on which they are wound, a stop device between the second and third rolls arranged to close the circuit through the clutch means to stop the machine if any of the threads are below a predetermined tension, a spreader between the stop and the second roll to divide the group of threads into two groups, a separator between the stop and spreader to separate the threads from each other before passing through the stop, a measuring drum between the third and fourth rolls, separating means between the last roll and the beam for guiding the threads to predetermined positions on the beam, and a pressing device bearing against the warp as it is wound on the beam.

6. A warp beaming device having means for rotatably supporting a beam, means for rotating the beam, means for connecting the beam in driving relation to the rotating means, an electrically actuated device for disconnecting the beam and rotating means,

a creel for supporting a plurality of separate thread supplying devices, an electric switch adjacent to the creel associated with each thread passing from the creel to the beam, guide rolls for the threads between the creel and the beam, individual thread guides between the rolls, and a second electric switch associated with each thread between the rolls, both sets of switches being electrically connected to the electrically actu-

ated device to control a circuit thereto to stop the machine if any one of said switches is actuated.

In testimony of which invention, I have hereunto set my hand, at Philadelphia, Pa., 15 on this 25th day of July, 1921.

JOHN W. SOHN.
